[57] CLAIM

The ornamental design for an egg carton, as shown and described.

DESCRIPTION

FIG. 1 is a plan view of an egg carton showing our new design;

FIG. 2 is a front elevation thereof;

FIG. 3 is a rear elevation thereof;

FIG. 4 is an end elevation taken from the right end;

FIG. 5 is a plan view of the open carton showing the outside of the carton top and the outside of the carton bottom;

FIG. 6 is a plan view of the open carton showing inside of carton bottom and the inside of the carton top;

FIG. 7 is an end elevation of open carton taken from the left side of the carton;

FIG. 8 is a longitudinal vertical section through the up-posts in the right half of the carton taken along line 8—8 on FIG. 1 and looking in the direction of the arrows;

FIG. 9 is a longitudinal vertical section through the center of the down-posts on the left half of the carton cover taken along line 9—9 on FIG. 1 and looking in the direction of the arrows;

FIG. 10 is a transverse vertical section through the transverse center of the open carton shown in plan view in FIG. 6, taken along line 10—10 on FIG. 6 and looking in the direction of the arrows;

FIG. 11 is an end elevation taken from the left end;

FIG. 12 is a longitudinal vertical section through the longitudinal center of the right half of the carton along line 12—12 on FIG. 1 and looking in the direction of the arrows; and

FIG. 13 is a transverse vertical section through the center of locking button and the up-posts on the carton cover taken along line 13—13 on FIG. 1 and looking in the direction of the arrows.

FIG. 1.

FIG. 2.

FIG. 3.

FIG. 4.
